UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR OPERATING VALVES OF ENGINES AND THE LIKE.

1,290,790.

Specification of Letters Patent.

Patented Jan. 7, 1919.

Application filed February 14, 1918. Serial No. 217,201.

To all whom it may concern:

Be it known that I, EUGÈNE SCHNEIDER, a citizen of the French Republic, and a resident of 42 Rue d'Anjou, Paris, France, 5 have invented new and useful Improvements in Apparatus for Operating Valves of Engines and the like, which invention is fully set forth in the following specification.

This invention has for its object to provide an improved apparatus for operating a plurality of valves (such as the valves of engines and the like) by a common member, such as for instance a lever or a rocking beam.

15 The improved apparatus in operating all the valves simultaneously, assures absolutely uniform amounts of lift and avoids all jamming of the valve stems in their guides.

For this purpose, according to this invention, the mechanism connecting the valves to be operated and the common operating member, comprises a part which has, according to the number of valves to be operated, for instance the shape of a crosshead, 25 carrying in all cases for each valve a projecting supporting finger which is adjustable and centered in the corresponding valve stem. This finger carrier is suitably guided by two axial projections in a box formed 30 on or fixed to the valve box, which limits its movements. Between these guiding projections, abutments are provided for the support of the end of the actuating rocking beam.

35 According to one embodiment of this invention the lower bearing or abutment of the rocking beam upon the finger carrier is provided by means of a block that is jointed to the end of the lever and has its underside adapted to be supported and to slide upon the faced surface of a bearing piece fixed in an axial lodgment in the said finger carrier.

This constructional form of the improved 45 apparatus is illustrated in detail in the accompanying drawings in which:

Figure 1 is a vertical section partly in elevation,

Fig. 2 is a horizontal section on the line 50 II-II of Fig. 1, and

Fig. 3 is a partial cross section on the line III-III of Fig. 1, of the said constructional form applied for the simulta-

neous operation of two valves by means of a common rocking beam.

55

Fig. 4 is a diagrammatic plan of a modification of the above form for operating simultaneously four valves having their axes arranged symmetrically in pairs in two planes at right angles to each other.

60

In these various figures, A indicates the valves to be operated; a are their stems which are guided in the usual manner in boxes B.

The common member for operating these 65 valves is constituted for instance by a rocking beam C-C¹ which is fulcrumed on a fixed axle D and receives through a pin E the motion that is imparted to it by the engine.

70

The connection between the arm C of the rocking beam and the valve stems a, is provided according to this invention by a part F which is guided by projections F¹, F², in a guide that is formed on or fixed to the 75 valve boxes. This guide for the sake of facility in erection is preferably made of two superposed parts G, H connected and fixed to the valve boxes by bolts I.

The arm C of the rocking beam terminates at its free end in a fork c carrying an axle pin c¹, on which is pivoted a block which with its faced surface j bears and slides upon a corresponding faced surface k of a bearing piece K fixed in the part F.

85

The said part F carries as many fingers f as there are valves to be operated (namely two in the example shown in Figs. 1 and 3, and four in the example shown in Fig. 4). These fingers f are formed at the ends 90 of screw-threaded rods engaged in corresponding internal screw-threads formed in the part F. The fingers f may be located at the ends of the arms for facility in construction and guidance. Each of these fingers which bears upon the head of the stem of the respective valve, is centered in the latter by means of a nipple f¹. The amount of projection of the finger beyond its supporting arm may be adjusted by means of 95 the nut f².

It will be perceived that the rocking motion of the rocking beam C in the requisite direction, will cause the finger carrier F to move down by the action of the block J, 105 and consequently will cause the valves to

be opened by the fingers $f-f^1$ bearing upon their stems. In the rocking movement of the rocking beam C-C¹ in the opposite direction, the action of the said rocking beam upon the finger carrier F and the valves does not take place. The valves are returned on to their seats by their springs which moves at the same time the finger carrier back into its initial position.

10 The finger carrier F is accurately centered in its guide G-H by the projections F¹, F², and will therefore execute a perfectly rectilinear movement and will produce in its turn a strictly rectilinear motion of the 15 valve stems.

In the example shown in Fig. 4, the part F has four arms the free ends of which carry the bearing fingers f projecting to an adjustable amount, each finger being centered by means of a nipple f^1 in its respective valve stem.

What I claim is:—

1. In an apparatus for operating a plurality of valves, such as engine valves and others, by means of a common operating member, such as a rocking beam, the combination with said common operating member, of means constituting a connection between the latter and the stems of the valves to be operated, comprising a finger-carrier, a plurality of adjustable fingers on said carrier equal to the number of valves to be operated, means for adjusting the projection of said fingers, a centering member on each of said fingers engaging in and centering the respective valve stem, guides on the valve boxes, oppositely located axial projecting members on said carrier working in

said guides, a bearing surface on said carrier between said guides, and a coöperating 40 pressing surface on the end of the rocking beam, whereby said carrier is actuated to operate the valves by the movement of the rocking beam.

2. In an apparatus for operating a plurality of valves, such as engine valves and others, by means of a common operating member, such as a rocking beam, the combination with said common operating member, of means constituting a connection 45 between the latter and the stems of the valves to be operated, comprising a finger-carrier, a plurality of adjustable fingers on said carrier equal to the number of valves to be operated, means for adjusting the projection 50 of said fingers, a centering member on each of said fingers engaging in and centering the respective valve stem, guides on the valve boxes, oppositely located axial projecting members on said carrier working in 55 said guides, a block pivoted on the end of the rocking beam, having a faced bearing surface, and a bearing member in said carrier, having a faced pressing surface coöperating with said faced bearing surface, 60 whereby said carrier is actuated to operate the valves by the sliding pressure of said faced pressing surface on said faced bearing surface.

In testimony whereof I have signed this 70 specification.

EUGÈNE SCHNEIDER.
